Primary Examiner—Doris Clark
Attorney, Agent, or Firm—Armstrong Teasdale Schlafly & Davis

[57] CLAIM

I claim the ornamental design for a convertible saw horse, as shown and described.

DESCRIPTION

FIG. 1 is a perspective view of a convertible saw horse showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrating a board is for illustrative purposes only and forms no part of the claimed design.
